(57) **CLAIM**

The ornamental design for an ergonomic lynch pin, as shown and described.

DESCRIPTION

FIG. 1 is a front view thereof an ergonomic lynch pin embodying our design with ring in partially open position; FIG. 2 is a side elevation view;

FIG. 3 is a rear plan view thereof, opposite that of FIG. 1; FIG. 4 is a side elevation view as seen from the opposite side of FIG. 2;

FIG. 5 is a top elevation view thereof as viewed from the top of FIG. 2;

FIG. 6 is a bottom elevation view thereof as viewed from the bottom of FIG. 2;

FIG. 7 is a perspective view of an ergonomic lynch pin embodying our design; and,

FIG. 8 is another perspective view of an ergonomic lynch pin embodying our design in the closed position as viewed from the front.
